(57) CLAIM

The ornamental design for solar pan with inserted form, as shown and described.

DESCRIPTION

FIG. 1 is a perspective view of a solar pan with inserted form showing our new design.

FIG. 2 is a top view of the solar pan with inserted form in FIG. 1.

FIG. 3 is a front end view of the solar pan with inserted form in FIG. 1.

FIG. 4 is a back end view of the solar pan with inserted form in FIG. 1.

FIG. 5 is a bottom view of the solar pan with inserted form in FIG. 1.

FIG. 6 is a left side view of the solar pan with inserted form inserted in FIG. 1; and,

FIG. 7 is a right side view of the solar pan with inserted form in FIG. 1.

The broken lines and spaced dotted broken lines shown represent unclaimed subject matter and form no part of the claimed design.
